UNITED STATES PATENT OFFICE.

ELI S. HART, OF CLINTON, IOWA.

TRACK-DRILL.

SPECIFICATION forming part of Letters Patent No. 286,298, dated October 9, 1883.

Application filed May 11, 1882. Renewed August 29, 1883. (No model.)

To all whom it may concern:

Be it known that I, ELI S. HART, of Clinton city, in the county of Clinton and State of Iowa, have invented certain new and useful 5 Improvements in Track-Drills; and I do hereby declare the following to be a full, clear, and exact description of the invention, such as will enable others skilled in the art to which it pertains to make and use the same.

10 My invention relates to drills, and more particularly to that class of drills adapted for drilling railroad-rails; and it consists in parts and combination of parts, which will be more fully hereinafter described and claimed.

15 In the drawings, Figure 1 is a view in elevation of a drill constructed according to my invention attached to a rail and in a position for operation. Fig. 2 is a plan view of the drill.

In the drawings, A represents the frame, 20 preferably made of metal, and adapted to hold and contain the operative parts of my device. This frame is provided with a nose, which bears against one side of the tread of the rail. To prevent lateral motion of the drill, when attached to the rail, it may be provided with two noses or points of contact, as shown in Fig. 2 of the drawings.

A' and A² are bearings for the sleeve and spindle.

30 A³ is a third bearing adapted to support the outer end of the shaft carrying the feeding mechanism of the drill.

B is a hollow upright adapted to support the frame c c, which affords bearings for the 35 main driving-shaft O. To this main driving-shaft are attached cranks P P.

D is the drill, preferably supported within the sleeve H.

G' is the spindle, to which the drill D is attached. This spindle is secured and made to revolve with the sleeve H by key attachment therewith.

V is a cam pivoted to the frame A, either by a shaft passing through it, said shaft turning in the bearings y y of the frame A, or in 45 any other suitable manner. This cam is operated by the lever V'. The object of this portion of my invention is to afford means by which the drill may be readily clamped to the 50 rail. I find by experience that a better grip can be obtained by the interposition of a wedge, W, between the face of the cam V and

the rail, although I do not limit myself to the use of this wedge; but when a wedge is used I prefer to make its inner face of converging 55 inclines, to bite the tread of the rail on one side, the opposite side of the wedge being circular in form, corresponding to the form of the face of the cam.

T is a feed-screw, which may be operated by 60 any of the well-known methods for feeding the drill to the rail as fast as it cuts.

N is a crown-gear keyed or otherwise secured to the main driving-shaft O. This meshes into another gear, M, which is permanently attached to the vertical shaft L within the upright sleeve B. To the other end of this vertical shaft L is secured another crown-gear, K, which in turn meshes with the crown gear F upon the spindle G.

70 The operation of my device is as follows: The machine is attached to the rail, and held rigidly in position by the bearing upon one side and cam V upon the other, which is forced against the rail Z. When the head of the rail is so small as to prevent the cam V from bearing sufficiently hard against it, a wedge, W, is interposed, as shown in Fig. 1. This manner of fastening the drill is far preferable to any of which I am aware, as it can be done 80 rapidly, and a single machine is adapted for fitting all sized rails. The machine having been thus firmly secured to the rail and in the proper place, the cranks P P are operated, which, by means of the gear-connection and 85 shaft L, drive the spindle carrying the drill, and the drill is set in motion. When the hole is completed, the drill is released and drawn back, and the lever V' being raised, the machine releases its grip upon the rail and is 90 ready for another operation.

75 What I claim is—

1. In a track-drill, the combination, with the drill, the horizontal and vertical shafts, and a frame provided with an arm or projection, X, which engages one side of the rail, of the cam V and cam-lever V', substantially as set forth.

2. In a track-drill, the combination, with the drill, the horizontal and vertical shafts, 100 and a frame provided with an arm or projection, X, which engages one side of the rail, of the cam V, cam-lever V', and wedge W, substantially as set forth.

3. In a track-drill, the combination, with
the drill, feeding-screw and wheel, upright
shaft, and driving-shaft, of the frame provided
with an arm that bears against one side of the
5 tread of a rail, and a cam and cam-lever for
securing the frame in place, substantially as
set forth.

In testimony whereof I have signed my name
to this specification in the presence of two sub-
scribing witnesses.

ELI S. HART.
